UNITED STATES PATENT OFFICE.

CHRISTOPHER OLIVER COLE, OF WHATCOM, WASHINGTON.

AUTOMATIC PIPE-COUPING.

SPECIFICATION forming part of Letters Patent No. 757,888, dated April 19, 1904.

Application filed August 21, 1903. Serial No. 170,302. (No model.)

To all whom it may concern:

Be it known that I, CHRISTOPHER OLIVER COLE, a citizen of the United States, and a resident of Whatcom, in the county of Whatcom and State of Washington, have invented a new and Improved Automatic Pipe-Coupler, of which the following is a full, clear, and exact description.

The invention relates to pipe-couplings for connecting air, steam, or other pipes of cars in a train with each other to form continuous pipe-lines.

The object of the invention is to provide a new and improved pipe-coupler which is completely automatic in operation and insures a firm coupling of the pipes for the various lines without danger of leakage, allows automatic uncoupling on moving the uncoupled cars apart, and permits a manually-controlled release of the coupling members whenever it is desired to do so by the operator.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional plan view of the improvement as applied, showing parts of the two coupling-heads in a coupled position. Fig. 2 is a side elevation of the same, parts being broken out. Fig. 3 is an enlarged sectional plan view of the improvement, showing the parts of two coupled heads in a coupled position. Fig. 4 is an enlarged sectional side elevation of part of the automatic releasing device. Fig. 5 is a transverse section of the same. Fig. 6 is a perspective view of the free end of another of the coupling members; and Fig. 7 is an enlarged sectional side elevation of the improvement, showing the parts of another coupling-head in an uncoupled position.

The coupling-heads A A' are supported on the ends of adjacent cars B B' and are alike in construction, and each contains the same

mechanism—that is, each head is provided near its mouth, spaced from one side, with an internal vertically-disposed fixed part A², on which is fulcrumed a pipe carrying coupling member C, mounted to swing transversely and projecting forwardly through the mouth of the coupling-head to readily enter the opposite coupling-head on coupling the cars B and B' together.

The coupling member C is provided between its ends with a transverse pipe-section D', forming a portion or a section of the train-pipe D of the train, and the pipe-sections D' of the coupled coupling members C C are in register with each other to form a connection through the coupling members and the flexible hose-sections D² D² of the train-pipe, the said sections leading from the pipes D' to piston-valves E E, located in the coupling-heads A A' and into which open the ends of the train-pipes D of adjacent cars B B'.

The free end of each coupling member C is provided with a rounded-off head C', adapted to fit a correspondingly rounded-off inner portion or seat A³ on the fixed part A² of the opposite coupling-head, and the said rounded-off head C' of a coupling member is moved to its seat and locked thereon by a transversely-movable block F, having an elongated vertical aperture F', through which extends a guide-pin F², secured in the top and bottom of the corresponding coupling-head A or A'. The inner face of the block F corresponds in shape to the outer side of the coupling member C, and the outer face of the block F is beveled to be engaged by a wedge G, arranged to travel lengthwise in the coupling-head between the block F and the inner face of the coupling-head side adjacent to the block, as plainly indicated in Figs. 1 and 3.

The wedge G is preferably provided with friction-rollers G', traveling on the said beveled outer face of the block F and the inner face of the coupling-head side, so as to reduce the friction between the wedge and the block and coupling-head to a minimum. Now when the wedge G is moved forwardly then the block F is caused to move transversely to engage the free end of the coupling member

C of the opposite coupling-head to move this free end of the coupling member onto its seat on the fixed part A².

Each of the coupling members C is provided 5 on its outer face with a segmental catch C², adapted to engage one of two notches A⁴ A⁵, formed in the corresponding fixed part A², so as to hold the coupling member C either in coupled position, as shown in Figs. 1 and 10 3, or in uncoupled angular position, as illustrated in Fig. 7—that is, when the coupling member C is in this latter position the catch C² engages the notch A⁵.

Near the inner end of the block F and at 15 the inner face thereof is arranged a recess F³, in which is guided the cross-bar H of a rod H', made hollow and mounted to slide lengthwise in a guideway A⁶, fixed in the coupling-head A or A', and on the end of the said rod 20 H' is secured one end of a spring H², fulcrumed with its other end on a cap H³, mounted to slide in the hollow rod H', and on the said cap H³ is attached one end of the valve-stem I' of a piston-valve I, having pistons I² 25 and I³, secured on and spaced from each other on the stem I', as plainly illustrated in the drawings. The pistons I² and I³ are mounted to slide lengthwise in a casing I⁴, and the piston I³ is pressed on by a spring I⁵, contained 30 in the rear end of the casing I⁴, and the tension of this spring can be regulated by an adjusting-screw I⁶, screwing in the end of the casing I⁴. The spring H² serves to hold the rod H' and its cross bar or head normally in 35 a forward position and to allow the said rod to slide a greater distance than is necessary to shift the pistons I² I³ of the piston-valve I. The tension of the spring H² increases on pulling the spring apart, and the said spring is 40 somewhat stronger than the spring I⁵ to allow compression of the latter before expanding the spring H². Thus when the rod H' is pushed rearward the piston-valve is opened, and when the piston I³ is pushed rearward until seated on the stop I⁷ and a further rearward motion is given to the rod H' then the spring H² stretches to allow such rearward motion of the rod without injuring the piston-valve or disturbing the latter's position. 45

50 Into the casing I⁴, between the pistons I² and I³, open two pipes D³ and J, of which the pipe D³ is a branch of the train-pipe D, so that train-line pressure can pass by way of the said branch pipe D³ into the casing I⁴, between 55 the pistons I² and I³, when the latter are in the position shown in Figs. 1 and 3, so that this train-line pressure can pass into the pipe J, containing a check-valve J' and opening into the casing K' of a second piston-valve K, 60 having pistons K² and K³. This casing K' is connected by a pipe K¹ with the rear end of a cylinder L, extending longitudinally in the rear portion of the coupling-head A, and in the said cylinder L is mounted to reciprocate 65 a piston L', normally held in a rearmost po-

sition in the cylinder L by a spring L², (see Fig. 7,) the said spring resting with one end against the forward end of the cylinder and pressing with its other end against the outer face of the piston L'.

The piston L' is provided with a hollow piston-rod L³, extending forwardly, and into which projects the stem G² of the wedge G, so that the latter is moved longitudinally forward or rearward, according to the movement 75 of the piston L' in the cylinder L, as herein-after more fully described.

The stem G² has a rear enlarged end G³, on the rear end of which is secured a cap G⁵, fitted to slide in the inner end of the hollow 80 piston-rod L³, in the forward end of which is arranged a cap G⁶, held adjustably in the piston-rod L³ by set-screws G⁷, screwing in the outer end or head of the said hollow piston-rod L³. A pull-spring G⁴ is connected at its 85 ends to the said caps G⁵ and G⁶, and the tension of the said spring can be regulated by the set-screws G⁷.

The spring G⁴ is arranged to resist a pull and is of sufficient strength to press the wedge 90 G into position, and a pressure of about ten pounds is required to overcome the spring sufficiently for forcing the cap G⁵ back against the piston L'.

Now when the piston L' is in its rearmost 95 position, as shown in Fig. 7, then the wedge G is withdrawn and the block F is in a side-wise position to allow ready entrance of the coupling member C of the opposite coupling-head A', and when the coupling-heads A and A' have been brought together and the coupling member C of the head A' has passed into the coupling-head A and pressed the cross-bar H into a rearmost position to cause the pistons I² and I³ to connect the pipes D³ and J 100 with each other then the air from the train-pipe passes through the pipe D³, casing I⁴, pipe J, casing K', and pipe K¹ into the rear end of the cylinder L to push the piston L' outward therein against the tension of the 105 spring L² to cause a forward movement of the wedge G for the latter to impart a transverse movement to the block F, so that the latter pushes the coupling member C of the coupling-head A' against its seat A³ and locks it 110 thereon. When the piston L' moves into a forward position, as described and shown in Figs. 1 and 3, then the said piston uncovers 115 an outlet-pipe N, having two branch pipes N' and N², of which the latter leads to a piston-valve E, connected with the train-pipe D, and the branch pipe N' connects with a passage N³, formed in the fixed part A² and adapted to register with a passage N⁴ in the coupling member C of the opposite coupling-head, and the outer end of the passage N⁴ in each coupling member C connects by a hose or flexible pipe N⁵ with a pipe N⁶, having a check-valve N⁷, leading to the pipe J, between the casing 120 K and the check-valve J'. 130

Now by the arrangement described operating-line is provided for extending through both coupling-heads, so that the air from the cylinder L in the coupling-head A can pass 5 by way of its pipe N through the pipe N', passages F³ and N⁴, and pipes N⁵ and N⁶ to the piston-valve K in the other coupling-head A' to then pass into the cylinder L in this coupling-head and force the piston L' therein outward; so as to cause the wedge G in this coupling-head A' to move its block F transversely 10 to force the coupling member C of the coupling-head A to its seat on the fixed part A² of the coupling-head A'. Now when the piston L' in the cylinder L of the coupling-head A' passes beyond the outlet-pipe N then air can 15 pass from the cylinder by way of this outlet-pipe N and its branch pipe N', the passage N³ in the fixed part A² of the coupling-head A', and the registering passage N⁴ in the coupling member C of the coupling-head A to the flexible pipe N⁶ in the head A, and by way of the pipe N⁶ and check-valve N' to the pipe J of the coupling-head A. Thus an operating-line 20 is established between the cylinders L of the two coupling-heads A and A'. Now the spring L² is pressed to, say, about twenty pounds, and as the air-pressure in the train-pipe D is about forty pounds it is evident that after the operating-line is established air under forty 25 pounds of pressure again passes by way of the pipe N and pipe N² into the rear end of the casing O' of the third piston-valve E, so as to move the pistons O² O³ therein in a forward direction against a regulating-spring O⁴, the tension of which is adjusted by a set-screw O⁵, say, to about forty pounds. Now when the pistons O² and O³ move forward then connection is established between the train-pipe D 30 and the pipe-section D² by way of the casing O', so that train-line pressure now passes from the forward car having the coupling-head A by way of the piston-valve E and pipe-section D² to the pipes D and D' in the coupled coupling members C C of the two heads A A', so 35 as to direct the air-pressure to the car B' and the brake mechanism thereon.

It is evident that any number of pipes may be registering sections in the coupling members C C of adjacent coupling-heads A A', the same as the pipes D or D', to allow of conducting steam or other fluid through said registering pipes from one car to another.

The withdrawal of the wedge G from a block 40 F and unlocking of the corresponding coupling member C can be accomplished either manually or automatically in the following manner: In the pipe K⁴ is arranged a three-way valve P, having its valve-stem P' extending to the outside of the coupling-head A or A', and on this outer end of the stem P' is arranged 45 a handle P², adapted to be taken hold of by the operator to turn the valve K so as to connect the cylinder end of the pipe K⁴ with the atmosphere to shut off the cylinder L from the

casing K' of the second piston-valve K. Now when the cylinder L is connected with the atmosphere by way of the valve P then air escapes from this cylinder, and consequently the pressure against the piston L' is reduced 50 to such an extent that the spring L² forces the piston L' back into a rearmost position, and in doing so the piston withdraws the wedge G to allow the block F to move transversely 55 to unlock and release its coupling member C. 75

When no use is made of the three-way valve P for releasing purposes, as above described, then a release is effected automatically on uncoupling the cars—that is, on moving the coupling-heads A and A' apart—and this automatic arrangement is as follows:

In the forward end of the casing K' in front of the piston K³ of the second piston-valve K is arranged the air-outlet K⁵, and when the pistons K² and K³ are drawn forwardly, as 80 hereinafter more fully described, then the pipe J is closed by the piston K² and the cylinder L is connected by way of the casing K' and the air-outlet K⁵ with the atmosphere to allow the air to escape from the cylinder L 85 for the piston L' to return to a rearmost position by the action of the spring L².

The forward end of the piston K³ is provided with a hollow piston-stem K⁶, mounted to slide in a bearing in the fixed part A² of 90 the head A or A', and into the said hollow piston-stem K⁶ extends a rod Q, mounted to slide lengthwise in a bearing A⁸, attached to the coupling-head A or A'. On the rod Q within the stem K⁶ is formed a head Q', on 95 one side of which presses a spring Q² and on the other side of the head Q' presses with equal force a spring Q³, as plainly shown in Fig. 3, the springs being contained in the hollow stem K⁶. The springs Q² and Q³ are 100 sufficiently strong to impart the least movement backward or forward of the rod Q to the pistons K² and K³. The springs Q² and Q³ allow the rod Q to move farther backward or forward than is required for the travel of 105 the pistons K² and K³.

The outer end of the rod Q is provided with an apertured head Q⁴, engaged by the lower end of a lever R, fulcrumed at R' on the coupling-head A or A', and the upper end 115 of the said lever R' is engaged by the pivot R² of a link R³, extending through an opening in the coupling-head A or A', to connect at its outer end by a chain or other flexible connection R⁴ with the draw-head B² of the car B or B', as illustrated in Fig. 2. The pivot R² extends in a bracket R⁵, having spaced notches R⁶ and R⁷, in either of which the pivot is held by springs R⁸, pressing on top of the pivot R², as plainly illustrated in 120 Figs. 4 and 5. Now when a great strain is exerted on the link R³ in a rearward direction then the pivot R² passes from the notch R⁶ to the notch R⁷ against the tension of the spring R⁸, and when the strain is in a reverse direction 125 130

tion then the pivot-pin R^2 passes from the notch R^7 back into the notch R^6 .

Now when the two cars B' and B' are drawn apart after being uncoupled in the usual manner a swinging motion is given to the lever R from the draw-head B^2 by way of the flexible connection R^4 and link R^3 , so that the rod Q is moved forwardly, and in doing so compresses the spring Q^3 , which in turn imparts 10 a longitudinal movement to the stem K^6 and the pistons K^2 K^3 to move the latter into the position above described—that is, to connect the pipe K^4 with the air-outlet K^5 for discharging the air from the cylinder L . The 15 swinging motion imparted to the lever R by way of the flexible connections causes the link R^3 to pull the pivot R^2 back to its rearmost notch R^7 in the bracket R^5 , and the pivot is held in this position until the heads A and A' 20 are pushed back.

The coupling-heads A and A' are by the flexible connection R^4 and link R^3 suspended from the draw-bar B^2 , as described, and the rear end of each coupling-head A and A' has a flexible suspension S from the timber B^3 of the car B' or B , and this flexible suspension allows longitudinal movement of the head A , as well as sidewise or up-and-down movement in any direction. For this purpose the rear end of 25 each coupling-head A (see Figs. 1 and 2) is provided with a cylindrical offset A^9 , on which is mounted to slide longitudinally a sleeve S' , having stop-pins S^2 , extending into elongated longitudinal slots A^{10} , formed in the offset A^9 . 30 The rear end of the sleeve S' has a reduced portion S^3 , engaged by one end of a spiral spring S^4 , held on the reduced end S^5 of a bracket S^6 , bolted or otherwise fastened to the car-timber B^3 , and on this bracket S^6 is 35 held one end of a second coil-spring S^7 , somewhat larger in diameter than the spring S^4 and inclosing the latter, the forward or free end of the spring S^7 loosely engaging the rear end of the sleeve S' .

Now by the arrangement described the sleeve S' has a free longitudinal sliding movement on the offset A^9 to allow forward or backward movement of the coupling-head A or A' , and by having the springs S^4 S^7 the coupling-head A or A' is free to flex in any direction and at the same time allows a rearward movement of the coupling-head and compression of the springs, so as to insure a proper coupling of the heads A and A' when they 50 come together on coupling up the cars B and B' .

The lever R , previously mentioned, can be actuated from the sleeve S' of the flexible suspension S , and for this purpose the said sleeve S' is provided with an apertured lug 60 S^8 for the passage of a rod R , pivotally connected with the lever R . Stop-collars T^1 and T^2 are secured on the rod T and are adapted to abut against opposite sides of the lug S^8 , so as to impart a longitudinal movement to

the rod T to swing the lever R for opening 65 and closing the second piston-valve K in the manner above described.

The pull on the heads A and A' causes a sliding motion of the offset A^9 in the sleeve S' , whereby the lug S^8 is drawn back to allow the 70 stop-collar T^1 and parts connected therewith to move backward for closing the second piston-valve K . The latter remains closed until the heads A and A' are pushed back either by hand or by the couplers coming together. On 75 the couplers coming together the offset A^9 is pushed inward in the sleeve S' , so that the stop-collar T^1 is moved against the lug S^8 , so that the link R^3 is moved forward, thereby causing the pivot R^2 to move to its forward 80 notch R^7 in the bracket R^5 . By this movement the stem Q is actuated for opening the piston-valve K .

The operation is as follows: When the coupling-heads A and A' are uncoupled, then each 85 has its coupling member C standing in an angular position, as plainly illustrated in Fig. 7, and the first piston-valve I has its pistons I^2 and I^3 in a forward position to disconnect the pipes D^3 and J . The second piston-valve K 90 is in the position as shown—that is, its pistons K^2 and K^3 connect the pipes K and K^4 with each other, while the other piston-valve E closes the train-pipe D and the pipe-section D^2 . Now when the coupling-heads A and A' 95 come together on coupling up the cars B and B' then the coupling member C of one coupling-head engages the beveled outer end of the block F in the opposite coupling-head to impart a sidewise swinging motion to the 100 coupling member for the latter to engage the cross-bar H to actuate the first piston-valve I , as above described, to connect the pipes D^3 and J with each other for the air to pass into the cylinder L to move the piston L' outward, so that the wedge G moves the block F transversely to lock the coupling member C in position on its seat A^9 . The operating-line is 105 brought into use as soon as the piston L' uncovers the pipe N , so that the third piston-valve E is finally actuated after the coupling members C are coupled together and locked in place to allow the passage of the train-line pressure from one part to the other and allow steam and the like to pass through their corresponding pipes attached to the coupling members C .

Uncoupling takes place either manually by the operator turning the handle P^2 or on pulling the heads A and A' apart on uncoupling the cars, as above described.

Having thus described my invention, I claim as new and desire to secure by Letters Patent—

1. An automatic pipe-coupler having coupling-heads, pipe-carrying coupling members in the said heads, and pneumatically-controlled means in each coupling-head for moving the said members into a coupling position, the

means in one head being automatically controlled by the coupling member of the other head, as set forth.

2. An automatic pipe-coupler having coupling-heads, pipe-carrying coupling members in the said heads, and pneumatically-controlled means for moving the said members into a coupling position and locking the same therein, as set forth.

10 3. An automatic pipe-coupler having coupling-heads, pipe-carrying coupling members in the said heads, pneumatically-controlled means for moving the said members into a coupling position and locking the same therein, and a manually-controlled releasing device for the said means, to unlock the members, as set forth.

4. An automatic pipe-coupler having coupling-heads, pipe-carrying coupling members 20 in the said heads, pneumatically-controlled means for moving the said members into a coupling position and locking the same therein, and a releasing device, controlled by the heads on separating the same, as set forth.

25 5. An automatic pipe-coupler having coupling-heads, pipe-carrying coupling members in the said heads, pneumatically-controlled means for moving the said members into a coupling position and locking the same therein, and an automatic releasing device for the said means, as set forth.

30 6. An automatic pipe-coupler having coupling-heads, pipe-carrying coupling members in the said heads, and pneumatically-controlled means for moving the said members into a coupling position and locking the same therein, the means in one head being actuated by the coupling member of the other head, as set forth.

35 40 7. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, and a pneumatically-controlled 45 wedge in each coupling-head, for engaging and moving the said block, as set forth.

45 50 8. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, and pneumatically-controlled means in each coupling-head, actuated by the entering coupling

member and connected with the corresponding wedge, as set forth.

9. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, and pneumatically-controlled means in each coupling-head, actuated by the entering coupling member and connected with the corresponding wedge, the said means comprising a piston-valve connected with the train-pipe, a second piston-valve connected with the first-named piston-valve, and a cylinder containing a piston connected with the said wedge, the said second piston-valve being connected with one end of the cylinder, as set forth.

10. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, and pneumatically-controlled means in each coupling-head, actuated by the entering coupling member and connected with the corresponding wedge, the said means comprising a piston-valve connected with the train-pipe, a second piston-valve connected with the first-named piston-valve, a cylinder containing a piston connected with the said wedge, the said second piston-valve being connected with one end of the cylinder, an outlet from the said cylinder, leading to a port in the said fixed part, and a pipe on the entering coupling member, adapted to connect with the said port, the said pipe connecting with the piston-valves in the other coupling-head, as set forth.

11. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, and pneumatically-controlled means in each coupling-head, actuated by the entering coupling member and connected with the corresponding wedge, the said means comprising a

6

piston-valve connected with the train-pipe, a second piston-valve connected with the first-named piston-valve, a cylinder containing a piston connected with the said wedge, the said second piston-valve being connected with one end of the cylinder, an outlet from the said cylinder, leading to a port in the said fixed part, a pipe on the entering coupling member, adapted to connect with the said port, the said pipe connecting with the piston-valves in the other coupling-head, a third piston-valve in each coupling-head, connected with the train-pipe and with the said outlet from the cylinder, and a pipe leading from the third piston-valve to the coupling member, to connect with the corresponding pipe in the other coupling member, as set forth.

12. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, pneumatically-controlled means in each coupling-head, actuated by the entering coupling member and connected with the corresponding wedge, and a releasing device for the said means, as set forth.

13. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, pneumatically-controlled means in each coupling-head, actuated by the entering coupling member and connected with the corresponding wedge, and a releasing device for the said means, controlled by the coupling-heads on separating the same, as set forth.

14. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, pneumatically-controlled means in each coupling-head, actuated by the entering coupling member and connected with the corresponding wedge, the said means comprising a piston-

valve connected with the train-pipe, a second piston-valve connected with the first-named piston-valve, a cylinder containing a piston connected with the said wedge, the said second piston-valve being connected with one end of the cylinder, and a releasing device connected with the said second piston-valve and controlled by the coupling-heads on separation of the same, as set forth.

15. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, pneumatically-controlled means in each coupling-head, actuated by the entering coupling member and connected with the corresponding wedge, the said means comprising a piston-valve connected with the train-pipe, a second piston-valve connected with the first-named piston-valve, a cylinder containing a piston connected with the said wedge, the said second piston-valve being connected with one end of the cylinder, and a three-way valve interposed in the connection between the said second piston-valve and the said cylinder, to connect the latter with the atmosphere, as set forth.

16. An automatic pipe-coupler having coupling-heads, pipe-carrying coupling members fulcrumed in the said heads, the member in one head being adapted to abut against a fixed part in the other head, a block movable in each coupling-head and adapted to engage the free end of the entering coupling member of the other head, to move the said entering coupling member against the said fixed part and lock it thereon, a wedge in each coupling-head, for engaging and moving the said block, pneumatically-controlled means in each coupling-head, actuated by the entering coupling member and connected with the corresponding wedge, the said means comprising a piston-valve connected with the train-pipe, a second piston-valve connected with the first-named piston-valve, a cylinder containing a piston connected with the said wedge, the said second piston-valve being connected with one end of the cylinder, an outlet from the said cylinder, leading to a port in the said fixed part, a pipe on the entering coupling member, adapted to connect with the said port, the said pipe connecting with the piston-valves in the other coupling-head, a third piston-valve in each coupling-head, connected with the train-pipe and with the said outlet from the cylinder, a pipe leading from the third piston-valve to the coupling member, to connect with the corresponding pipe in the other coupling member,

- and a releasing device connected with the said second piston-valve and controlled by the coupling-heads on the separation of the same, as set forth.
- 5 17. An automatic pipe-coupler having coupling-heads, pipe-carrying coupling members fulcrumed in the said heads, the member in one head being adapted to abut against a fixed part in the other head, a block movable in each 10 coupling-head and adapted to engage the free end of the entering coupling member of the other head, to move the said entering coupling member against the said fixed part and lock it thereon, a wedge in each coupling-head, 15 for engaging and moving the said block, pneumatically-controlled means in each coupling-head, actuated by the entering coupling member and connected with the corresponding wedge, the said means comprising a piston- 20 valve connected with the train-pipe, a second piston-valve connected with the first-named piston-valve, a cylinder containing a piston connected with one end of the cylinder, an outlet from the said cylinder, leading to a port in 25 the said fixed part, a pipe on the entering coupling member, adapted to connect with the said port, the said pipe connecting with the piston-valves in the other coupling-head, a third piston-valve in each coupling-head, connected 30 with the train-pipe and with the said outlet from the cylinder, a pipe leading from the third piston-valve to the coupling member, to connect with the corresponding pipe in the other coupling member, and a three-way valve 35 interposed in the connection between the said second piston-valve and the said cylinder, to connect the latter with the atmosphere, as set forth.
18. An automatic pipe-coupler having a 40 coupling-head adapted to receive a coupling member from an opposite coupling-head, a block movable in the coupling-head, to press the said entering coupling member against a fixed part in the said coupling-head, a wedge 45 for engaging and moving the said block in one direction, a pneumatic cylinder, and a spring-pressed piston therein, connected with the said wedge, as set forth.
19. An automatic pipe-coupler having a 50 coupling-head provided with a fixed part having a rounded-off portion, a coupling member fulcrumed on the fixed part and having its free end provided with a head adapted to fit the rounded-off portion of the fixed part in 55 the opposite coupling-head, and a catch on the said coupling member, adapted to engage spaced notches in the fixed part, to hold the
- coupling member in either of two positions, as set forth.
20. An automatic pipe-coupler having a releasing device for a piston-valve, controlled from the draft coupler-head of the car, as set forth. 60
21. An automatic pipe-coupler having a releasing device for a piston-valve, comprising 65 a lever engaging at one end the valve-stem of the piston-valve, a link pivotally connected with the said lever, a flexible connection between the link and the draw-bar, and a spring- catch for engaging the pivotal connection between the link and lever, to hold the connection in either of two positions, as set forth.
22. An automatic pipe-coupler having a releasing device for a piston-valve, comprising 70 a lever engaging at one end the valve-stem of the piston-valve, a link pivotally connected with the said lever, a flexible connection between the link and the draw-bar, a spring- catch for engaging the pivotal connection between the link and lever, to hold the connection in either of two positions, a coupling- 75 head on which the lever and catch are held, a spring-support for the coupling-head, provided with lugs, and a rod on the said lever, having stop-collars for engaging by the said 80 lugs, as set forth.
23. An automatic pipe-coupler provided 85 with a coupling-head, and a coiled-spring support for the rear end of the coupling-head, to allow longitudinal and sidewise motion of the coupling-head, as set forth.
24. An automatic pipe-coupler provided 90 with a coupling-head, a flexible suspension for suspending the forward end of the coupling-head from the draft-coupler head, and a 95 longitudinally-extending coiled-spring support for the rear end of the coupling-head, to allow longitudinal and transverse movement of the coupling-head, as set forth.
25. An automatic pipe-coupler provided 100 with a coupling-head having a rearwardly-extending hub, a sleeve slidable on the said hub, a fixed support, a spiral spring connecting the fixed support with the said sleeve, and a second spiral spring held on the said support 105 and freely engaging the sleeve, to abut against the said head, as set forth.

In testimony whereof I have signed my name to this specification in the presence of two subscribing witnesses.

CHRISTOPHER OLIVER COLE.
